UNITED STATES PATENT OFFICE

2,519,587

DESULFURIZING HYDROCARBON OILS

David A. McCaulay, Chicago, Ill., and Arthur P. Lien, Hammond, Ind., assignors to Standard Oil Company, Chicago, Ill., a corporation of Indiana

Application June 18, 1947, Serial No. 755,457

10 Claims. (Cl. 196—31)

1

This invention relates to a process for desulfurizing hydrocarbon oils. More particularly it relates to a process for the desulfurization of hydrocarbon oils containing hydrocarbon disulfides.

In the petroleum industry a number of hydrocarbon oils are produced which comprise sulfur compounds, including hydrocarbon disulfides. Particularly, the petroleum industry normally produces relatively light or low boiling hydrocarbon oils such as gasoline, naphtha, kerosene and heater oils which contain hydrocarbon disulfides. Thus, for example, mercaptan-containing (sour) gasoline condensed from natural gas, distilled from crude petroleum oils or derived from petroleum oil fractions by cracking operations is ordinarily subjected to so-called sweetening operations in the course of which the mercaptans in the gasoline are converted to gasoline-soluble disulfides which are retained in the gasoline.

Although hydrocarbon disulfides do not possess the foul odor of alkyl mercaptans, they markedly reduce the ability of lead alkyls such as lead tetraethyl to increase the octane number of the gasoline or naphtha in which they are present, i. e., they reduce the lead susceptibility of the fuel. It has been observed that of the various types of sulfur compounds, hydrocarbon disulfides appear to exert the greatest depressing effect on lead susceptibility (W. A. Schulze and A. E. Buell, National Petroleum News, 27, No. 41, page 25 (October 9, 1935)). Hydrocarbon disulfides are also undesirable components in hydrocarbon oils intended for use as fuels for the reason that in the combustion process they are converted to sulfur dioxide which, with the water generated in the combustion of hydrocarbons, tends to cause corrosion of metal surfaces with which it comes in contact.

Accordingly, it is an object of our invention to provide a process for desulfurizing hydrocarbon oils comprising sulfur compounds including hydrocarbon disulfides. Another object of our invention is to provide a process for converting hydrocarbon disulfides and olefins contained in hydrocarbon oils into valuable chemical products which can be recovered for employment in industry. An additional object is to provide a process for removing hydrocarbon disulfides and equimolecular amounts of olefinic hydrocarbons from hydrocarbon oils containing them, e. g., gasoline or kerosene. A further object is to provide a method for removing hydrocarbon disulfides and other sulfur compounds from light

2

hydrocarbon oils without substantially removing low boiling mononuclear aromatic hydrocarbons which possess high octane number.

One more object of our invention is to provide a process for removing hydrocarbon disulfides from a hydrocarbon oil containing substantially no olefinic hydrocarbons or containing an olefinic hydrocarbon in less than an equimolar amount based on its content of hydrocarbon disulfides. Still another object is to provide a method of simultaneously alkylating aromatic hydrocarbons contained in a light hydrocarbon oil with olefins and effecting the conversion of hydrocarbon disulfides and other sulfur compounds contained therein to compounds which are preferentially soluble in liquid hydrogen fluoride and are extracted from said oils by said liquid hydrogen fluoride, whereby both the clear octane number and lead susceptibility of the light hydrocarbon oil are improved. These and other objects of our invention will become apparent from the ensuing description thereof read in conjunction with the accompanying figures.

25 We have observed that hydrocarbon disulfides are dissolved only to a limited extent by concentrated liquid hydrogen fluoride at normal temperatures. However, we have discovered that hydrocarbon disulfides contained in a hydrocarbon oil can be reacted with olefinic hydrocarbons in the presence of concentrated liquid hydrogen fluoride to produce reaction products which appear to be almost entirely di-thioethers and which are extremely soluble in concentrated hydrofluoric acid at normal temperatures. Thus, 30 we have discovered a desulfurization process for the removal of hydrocarbon disulfides from hydrocarbon oils in which process concentrated liquid hydrogen fluoride functions both as a catalyst and as a solvent for the sulfur-containing reaction products, i. e. as a desulfurizing agent for the hydrocarbon oil. The reaction which appears to take place may be represented as follows:

35

40 wherein each R represents a hydrocarbon radical (usually an alkyl radical) and each R' may be hydrogen or a hydrocarbon radical.

45 Although our invention may be applied to the desulfurization of any hydrocarbon oil containing disulfides, it is believed that its application 50 will be of principal interest for the desulfuriza-

tion of relatively low boiling hydrocarbon oils such as gasolines, naphthas, kerosenes. Our invention may, however, be applied advantageously to furnace oil and the like.

Light hydrocarbon oils obtained from sour crudes contain a variety of alkyl mercaptans, including methyl, ethyl, n- and iso-propyl, n- and iso-butyl, n- and iso-amyl mercaptans and smaller amounts of higher alkyl mercaptans such as hexyl, heptyl and octyl mercaptans. In the sweetening process these mercaptans are converted to symmetrical and unsymmetrical alkyl disulfides.

In addition to hydrocarbon disulfides the hydrocarbon oil to be treated may contain aromatic hydrocarbons, particularly relatively low boiling mononuclear aromatic hydrocarbons such as benzene, toluene, xylenes, ethylbenzene, ethyltoluene, propylbenzene or butylbenzenes, and mono-olefinic hydrocarbons, in addition to the saturated hydrocarbons; surprisingly, these aromatics are soluble only to a very minor extent in liquid hydrogen fluoride at ambient temperatures. Thus, gasolines produced by thermal cracking of gas oils or other high boiling fractions of crude oil which have been sweetened by some conventional process such as "doctor" sweetening, or by copper salts adsorbed on clays, contain hydrocarbon disulfides, olefins and usually some aromatic hydrocarbons such as benzene, toluene and the like. Concentrated sulfuric acid, e. g. 90 to 98 weight per cent sulfuric acid, in the absence of olefins, converts mercaptans in hydrocarbon oils to disulfides and extracts a portion of the disulfides. Gasolines derived by condensation from "sour" natural gas or by non-cracking distillation of crude petroleum, followed by a sweetening operation, contain hydrocarbon disulfides but little or no olefinic hydrocarbons.

In applying our invention to hydrocarbon charging stocks containing disulfides but no olefinic hydrocarbons or less than an equimolar amount of olefinic hydrocarbons based on the disulfide content of the charging stock, it will be necessary to treat the charging stock with concentrated liquid hydrogen fluoride and an added olefin in quantity such that the total olefin available for reaction with the hydrocarbon disulfide is at least equimolar with respect to the disulfide. Thus in desulfurizing straight run, sweetened gasoline or kerosene it is necessary to react the charging stock with added olefin in an amount equimolar with the amount of hydrocarbon disulfide contained in the stock. When the amount of mono-olefinic hydrocarbons contained in the charging stock exceeds the hydrocarbon disulfide content of the stock, the treating conditions may be adjusted (by control of the amount of hydrogen fluoride, temperature and time) to effect the disulfide-olefin reaction and extraction described above without causing substantial polymerization or other reaction of the olefinic hydrocarbons present in the charging stock in excess of the amount of hydrocarbon disulfide.

A wide variety of mono-olefinic hydrocarbons may be added to the disulfide-containing charging stocks to adjust the disulfide: olefin mole ratio to about 1. Either individual olefins or mixtures of olefins may be employed. Mixtures of olefins with saturated hydrocarbons, e. g. as found in petroleum refinery fractions, may likewise be employed.

Thus the invention may be practiced with

acyclic mono-olefinic hydrocarbons, such as ethylene, propylene, 1- or 2-butene, isobutylene, pentenes, hexenes, decenes, dodecenes, cetenes, styrene, vinylacetylene, alpha-alkyl styrenes such as alpha-methyl styrene, alpha- or beta-vinyl-naphthalenes; polymers of the above and similar olefins, for example diisobutylene which is a mixture of 2,4,4-trimethyl-1- and 2-pentenes, propylene or isobutylene trimers and tetramers, and the like. The olefinic polymer employed may be depolymerizable under the reaction conditions to yield the monomeric olefin which will then enter into reaction with the hydrocarbon disulfide.

We may also employ cyclo-olefins, e. g., cyclohexene, methyl cyclohexenes, cyclopentene, methylcyclopentenes, terpenes, 3-vinylcyclohexene, cyclohexadiene-1,3-, p-benzoquinone.

Poly-olefins may also be employed in this invention, for example 1,3-butadiene, isoprene, 2,3-dimethyl-1,3-butadiene, cyclopentadiene, dicyclopentadiene, 1,4-pentadiene, 1,5-hexadiene, divinylbenzene and the like.

We may also employ a variety of substituted olefins in the practice of this invention, for example dichlorostyrenes, trifluoromethylvinylbenzenes; vinyl heterocyclic compounds such as vinylthiophenes, vinylfuranes and vinylpyridines; methylvinyl ketone; vinyl acetate, esters of crotonic, acrylic, methacrylic or sorbic acids, etc.

The process of the present invention may be practiced not only with olefinic compounds but also with materials capable of yielding these compounds under certain reaction conditions. Thus, as has been pointed out above, depolymerizable polymers may be employed as a source of olefin monomer for the reaction with a disulfide. Examples of such polymers are di-, tri- or tetra-isobutylenes. In the presence of acidic condensation catalysts certain highly branched chain paraffinic hydrocarbons undergo cleavage to yield olefinic hydrocarbons and may be employed as a source of olefins for the present invention; a suitable example of such a highly branched chain paraffin hydrocarbon is commercial isoctane which comprises predominantly 2,2,4-trimethylpentane. Cycloalkanes of highly strained ring structure such as cyclopropane and substituted cyclopropanes, e. g. methyl- or ethyl-cyclopropane, can function as a source of propylene or substituted propylenes in the presence of acidic condensation catalysts.

Certain derivatives of olefin hydrocarbons are unstable in the presence of acidic condensation catalysts and are capable of yielding olefins in their presence. This is especially true of derivatives of tertiary olefins. These derivatives comprise mercaptans, alcohols, ethers, halides and the like. Examples are tert.-butylmercaptan, ethanol, isopropanol, tert.-butanol, di-tert.-butyl ether, tertiary octyl chlorides, tert.-methylcyclopentyl chloride, tert.-butyl chloride, tert.-amyl chloride.

We prefer to carry out the process of our invention with commercial, liquid, substantially anhydrous hydrogen fluoride. However, the inclusion of relatively small amounts of water in the solvent-catalyst may be tolerated; thus the liquid hydrogen fluoride solvent-catalyst may contain up to about 10 weight per cent of water. In general, water tends to reduce the solvent capacity of hydrogen fluoride for sulfur compounds; therefore, we prefer to employ substantially anhydrous liquid hydrogen fluoride or

hydrogen fluoride containing no more than about 5 weight per cent of water.

The amount of hydrogen fluoride employed will vary somewhat with the particular charging stock, temperature, other operating conditions and the results sought. However, we ordinarily employ at least sufficient hydrogen fluoride to form a distinct acid phase, i. e., a phase in which liquid hydrogen fluoride is the predominant component. We may employ 5 to 100 per cent of commercial liquid hydrogen fluoride or even more, based on the volume of the hydrocarbon charge stock; ordinarily we employ between about 10 and about 30 volume per cent of liquid hydrogen fluoride based on the volume of the hydrocarbon charging stock.

It may sometimes be desirable to effect reaction of hydrocarbon disulfides with olefins and extraction of the reaction products, respectively, in two distinct stages. In the first stage the reaction between a hydrocarbon disulfide and an olefin may be effected in the presence of a small, catalytic amount of concentrated hydrogen fluoride insufficient to function efficiently as a solvent for the reaction products; for example, the reaction may be effected with between about $\frac{1}{10}$ and about 5 volume per cent of liquid hydrogen fluoride based on the volume of the hydrocarbon charging stock. When hydrogen fluoride is employed as a catalyst only it is preferred to employ an amount at least equimolar with respect to the amount of hydrocarbon disulfide contained in the hydrocarbon charging stock. In the second (extraction) stage, additional concentrated liquid hydrogen fluoride is added to the reaction mixture derived from the first stage in an amount sufficient at least to form a distinct acid phase. The acid phase contains the sulfur-containing reaction products, predominantly di-thioethers. When reaction and extraction are effected as distinct operations it may be desired to conduct each operation at a different temperature. Thus reaction may be effected at normal or elevated temperatures, for example, temperatures from about 50° F. to as high as about 250° F. and extraction may be effected at normal or reduced temperatures, for example, temperatures from 100° F. down to 0° F. or even lower, for example -20° F. or even -40° F.

Where olefin addition is necessary, the olefin may be added before, during or after the addition of the hydrogen fluoride to the charging stock. It is not necessary to employ pure olefins.

Ordinarily we may effect the desulfurization operation at ambient temperatures, although the temperature may be varied over a broad range, for example between about 0° F. and about 200° F. Usually the process of the invention is conducted at temperatures between about 50° F. and about 100° F., for example between about 60° F. and about 80° F.

The reaction between a hydrocarbon disulfide and a mono-olefinic hydrocarbon is exothermic and rapid at about room temperature. Accordingly, dependent upon the particular temperature HF:oil ratio, disulfide concentration in the oil, intimacy of contacting, etc., the period of contacting between the hydrogen fluoride, olefin and disulfide may be varied from about 1 minute or even less to about 10 minutes.

Sufficient pressure is maintained in the contacting zone and in the zone where the acid phase is separated from the desulfurized hydrocarbon charging stock to maintain at least a substantial proportion of the hydrogen fluoride

and charging stock in the liquid phase. Ordinarily pressures between about 0 and about 200 p. s. i. g. are suitable, e. g. a pressure of about 25 or 50 p. s. i. g.

5 The contacting and acid separation equipment heretofore employed in HF-catalyzed alkylation of isoparaffins with olefins can be employed in the practice of this invention. Thus the charging stock, hydrogen fluoride and added olefin 10 (if any) can be passed through a coil, which may be provided with baffles to induce mixing, and thence into a gravity settler or centrifuge; the coil may be immersed in a heat transfer bath to provide for removal of the heat generated in the reaction and to maintain the reaction temperature within desired limits. In another mode of operation, the charging stock, hydrogen fluoride and added olefin may be pumped through orifice mixers, venturis or other mixing devices 15 and thence into a gravity settler or centrifuge for effecting separation of desulfurized hydrocarbon and an acid phase containing extracted sulfur compounds. Other equipment and process flows will be specifically described in conjunction with the accompanying figures.

In the specific embodiment of our invention schematically illustrated in Figure 1, the contactor 10 is provided with a heat transfer jacket 11 through which a cooling fluid is circulated 20 during the contacting to remove heat generated by the reaction, thereby maintaining the contacting temperature within the desired limits. In order to effect intimate mixing, contactor 10 is provided with motor-driven stirring paddles 12.

35 The hydrocarbon charging stock containing hydrocarbon disulfides, e. g., a sweetened, straight run gasoline containing substantially no olefinic hydrocarbons is passed into the contactor through valved line 13. A mono-olefinic hydrocarbon, for example a refinery ethylene, propylene or butylene fraction can be charged into the contactor through valved line 14. If desired part or all of the olefinic material may be premixed with the hydrocarbon charging stock so that a blend of olefin and hydrocarbon charging stock will be charged to the contactor through line 13. It is preferred to charge an amount of olefin substantially equimolar with the amount of hydrocarbon disulfide contained in the hydrocarbon charging stock in order to achieve thoroughgoing desulfurization of said stock. However, it will be appreciated that less than an equimolar amount of olefin may be employed in any one contacting stage and that a number of contacting stages may be employed with the addition of olefin in each stage. Ordinarily it is undesirable to add more than an equal amount of olefin to the charging stock, unless it is desired also to effect olefin polymerization to increase the yield of hydrocarbon product from the desulfurization process. Also, it may be desirable to add more than an equimolar amount of olefin, based upon the amount of hydrocarbon disulfide, when it is desired to effect alkylation of aromatic hydrocarbons or isoparaffinic hydrocarbons which may be present in the hydrocarbon charging stock.

60 Fresh concentrated liquid hydrogen fluoride is charged into the contactor from source 15 through valved line 16, e. g., in an amount equivalent to about 20 per cent by volume based on the volume of hydrocarbon charging stock. It is desirable to avoid extensive or prolonged contact of the liquid hydrogen fluoride with the olefin in the absence of the charging stock containing hydrocarbon disulfides, since contact may lead to un-

desirable reactions such as olefin polymerization accompanied by hydrogen disproportionation, whereby the effective concentration of olefin is appreciably reduced in the contacting zone.

In contactor 10 the charging stock, olefin and hydrogen fluoride are agitated at a rate sufficient to cause intimate admixture at a suitable temperature, for example about 60° F. to about 80° F. for a suitable period, for example about 1 hour, and are then discharged through valved line 17 into a cooler 18 where the temperature of the mixture is adjusted to a desirable value for the subsequent step of separating the hydrocarbon and acid phases. If desired, additional concentrated liquid hydrogen fluoride may be added to the mixture in line 17 through valved line 19.

From cooler 18 the mixture passes through line 20 into a settler 21 wherein desulfurized hydrocarbons are separated from a liquid hydrogen fluoride phase containing sulfur compounds. Although the settler is depicted as a gravity settler, it will be appreciated that a centrifuge could be employed instead. If desired, the settler may be provided with packing to serve as an aid to stratification. Suitable packing materials comprise shaped fragments of carbon, copper, Monel metal, carbon steel and certain magnesium alloys containing minor amounts of aluminum and still smaller amounts of other alloying elements such as zinc or manganese (Dowmetals). The settler is equipped with an overhead valved vent line 22 through which light gases may be released to adjust the pressure to a desired value. Suitable operating conditions for the settler comprise a temperature between about 60° F. and about 120° F. and pressures between about 0 and about 40 p. s. i. g. In the settler are formed a lower phase in which liquid hydrogen fluoride is the predominant component and an upper hydrocarbon phase of diminished sulfur content. The hydrocarbon phase is withdrawn through valved line 23 through a hydrogen fluoride stripping zone 24 wherein dissolved or dispersed hydrogen fluoride is vaporized, optionally at pressures below atmospheric and/or with the aid of stripping gases such as methane, ethane, propane, butane, pentane, etc. From the stripping zone the hydrocarbon passes through valved line 25 to storage or to such ulterior treatment, e. g., neutralization, as may be desired.

Residual hydrogen fluoride may be removed from the hydrocarbon oil by washing with alkaline materials, e. g. caustic soda; by passage over metal fluorides, e. g., sodium or potassium fluorides or hydrofluorides; by passage over adsorptive materials such as activated alumina, chromium oxide-alumina, silica gel, activated carbon and the like.

When unsaturated hydrocarbon charging stocks are employed, alkyl fluorides are usually formed therein. The alkyl fluorides have detrimental effects on the octane number of hydrocarbon fuels and should be removed therefrom. A number of methods are available for defluorination, including high temperature treatment with bauxite and the like.

The acid phase is discharged from the settler through valved line 26, whence part or all thereof may be recycled to contactor 10 through valved line 27, heat exchanger 28 in which its temperature is brought to the desired value for the contacting operation, and valved line 16. It is desirable to pass at least a part of the acid phase from the settler through valved line 29 and heater

30 into a zone in which the hydrogen fluoride and sulfur compounds in solution therein are separated.

Where the recovery of hydrogen fluoride is unimportant and the principal object is to separate the sulfur compounds, the acid may be diluted with water or neutralized, whereupon the sulfur compounds, notably di-thioethers, separate as an immiscible liquid phase which may be washed with water and fractionated into close boiling fractions which may have industrial value. Ordinarily it is desirable to separate hydrogen fluoride in suitable form for reuse in the contacting operation. It is, therefore, desirable to subject the acid phase from the settler to a fractionation operation. This may be effected in fractionator 31. In order to aid the vaporization and withdrawal of hydrogen fluoride, a stripping gas, which may form a minimum-boiling azeotrope with hydrogen fluoride may be introduced into the lower portion of the fractionator through valved line 32. Suitable stripping gases include methane, ethane, propane, butanes and pentanes. If desired, fractionator 31 may be operated at a subatmospheric pressure. Hydrogen fluoride is vaporized in the fractionator and passes overhead through valved line 33 for condensation and reuse in contactor 10.

The higher boiling sulfur compounds are withdrawn from the fractionator through valved line 34. They may be freed from traces of acid by washing with alkalies and water or by passage over materials capable of adsorbing or combining chemically with hydrogen fluoride.

Figure 2 illustrates another embodiment of our invention wherein counterflow contacting of the hydrocarbon charging stock with liquid hydrogen fluoride and separation of a desulfurized hydrocarbon phase and an acid phase enriched in sulfur compounds are effected in one tower. Desulfurization tower 100 is provided with contacting means 101, for example shaped packing materials such as fragments of carbon, copper, Monel metal, carbon steel, magnesium alloys, etc. Heat exchange coils 102 are provided in the contacting section of the tower to aid in controlling the temperature. Hydrogen fluoride is admitted into the tower from a source, such as storage tank 103, valved line 104 and line 105, passing into the upper portion of the contacting zone in the tower, whence it passes downwardly to the lower end of the tower. The hydrocarbon charging stock containing hydrocarbon disulfides is passed into the lower portion of the contacting zone in the tower through valved line 106 and rises through the contacting zone against the counterflow of liquid hydrogen fluoride. The desired amount of olefin is added to the hydrocarbon charging stock through valved line 107. The upper end of the tower, above the contacting zone, serves as a settling zone for the desulfurized or partly desulfurized hydrocarbon charging stock which is withdrawn therefrom through valved line 108, whence it may be withdrawn through hydrogen fluoride stripping zone 109 and discharged from the system through line 110. It is usually desirable to neutralize traces of hydrogen fluoride which may be contained in the oil leaving the system through line 110.

Part of the partly desulfurized hydrocarbon stock may be recycled to the contacting zone in tower 100 through valved line 111, heat exchanger 112 and valved line 106. The acid containing dissolved sulfur compounds settles into the lowermost portion of tower 100 whence it is withdrawn through valved line 113 and may be recycled to

the contacting zone through pump 114, valved line 115, cooler 116 and line 105. It is, however, desirable to pass part or all of the acid phase from tower 100 through valved line 117 and heater 118 into a fractionator 119. In the fractionator, hydrogen fluoride is vaporized and passed overhead through valved line 120, whence at least a portion of the hydrogen fluoride vapors may be removed from the system through valved line 121; preferably part or all of the hydrogen fluoride vapors are passed through valved line 122 and condenser 123 for recycle through line 105 to the desulfurization tower 100. To aid in the vaporization of hydrogen fluoride in the fractionator, a stripping gas is passed through valved line 124 and/or the fractionator may be operated at a subatmospheric pressure. Sulfur compounds are withdrawn from fractionator 119 through valved line 125. Gases which may accumulate in the system may be removed from the desulfurization tower 100 through a valved vent line 126.

The following examples are introduced in order to illustrate but not unduly to limit the scope of the process of this invention.

Example 1

A solution of n-octyl disulfide and n-heptane was prepared containing 1.50 weight per cent of sulfur. This solution was agitated for 1 hour at room temperature with 200 cc. of commercial liquid, substantially anhydrous hydrogen fluoride per liter of the solution, after which agitation was discontinued and the contacting mixture was allowed to separate by gravity into an upper hydrocarbon phase and a lower acid phase. Sulfur analyses of the phases indicated that only 9 weight per cent desulfurization of the n-heptane had occurred. Under otherwise identical operating conditions but with the addition of 1 mol of diisobutylene per mol of disulfide contained in the n-heptane, 95 per cent desulfurization of the n-heptane occurred. Since diisobutylene depolymerizes readily, one mol thereof can be considered as the substantial equivalent of two mols of isobutylene. It is apparent that the disulfide reacts with the olefin to produce a sulfur compound which is far more soluble in liquid hydrogen fluoride than n-octyl disulfide, which under the conditions of this experiment was relatively insoluble in liquid hydrogen fluoride. It appears that the HF-soluble sulfur compound which is produced when an olefin is added is a di-thioether.

Example 2

A solution of ethyl disulfide in n-heptane was prepared containing 5.6 weight per cent of sulfur. The solution was agitated for 1 hour at room temperature with 200 cc. of commercial, substantially anhydrous hydrogen fluoride per liter under ethylene pressure, after which the pressure on the contacting mixture was reduced to atmospheric by bleeding off excess ethylene gas and the mixture was allowed to separate by gravity into an upper hydrocarbon phase and a lower acid phase. Sulfur analyses of the two phases indicated that 99 weight per cent desulfurization of the n-heptane had occurred. In the absence of an added olefin desulfurization to the extent of only about 60 weight per cent could be expected.

Although we have specifically described the desulfurization of hydrocarbon oils containing hydrocarbon disulfides by reaction and extraction with liquid hydrogen fluoride and a mono-olefinic hydrocarbon, it will be appreciated that other organic compounds containing olefinic unsatur-

ation might be used instead. Although we have emphasized the reactions of hydrocarbon disulfides with olefins in the presence of liquid hydrogen fluoride as a catalyst and solvent for the product, it is appreciated that the liquid hydrogen fluoride may exert more or less solvent capacity for other sulfur compounds which may be present in the hydrocarbon charging stock, for example: thiophenes, thiophanes or thioethers. Mercaptans react with olefins in the presence of liquid hydrogen fluoride as a catalyst-solvent to form thioethers which are extracted by the hydrogen fluoride from the hydrocarbon charging stock. Thioethers are far more soluble in liquid hydrogen fluoride than the corresponding mercaptans.

The general reaction of organic disulfides with olefinic hydrocarbons in the presence of chemical compounds which are acidic chemical condensation catalysts to effect the preparation of dithioethers is claimed in applicants' copending application for U. S. Letters Patent, Serial No. 755,456, filed of even date herewith.

Having thus described our invention, what we claim is:

- 25 1. A process which comprises sweetening a mercaptan-containing hydrocarbon oil to produce a hydrocarbon oil containing disulfides, adding an olefinic hydrocarbon to the sweetened oil in an amount sufficient to increase the molar ratio of olefinic hydrocarbons to disulfides to at least one, contacting the sweetened hydrocarbon oil in the presence of said olefinic hydrocarbon with liquid hydrogen fluoride in quantity sufficient at least to form a distinct liquid phase at a temperature between about 0° F. and about 200° F. under a pressure sufficient to maintain the liquid phase, thereby effecting chemical reaction between said disulfides and said olefinic hydrocarbon to produce a hydrogen fluoride-soluble sulfur-containing reaction product, and thereafter separating a hydrocarbon oil of reduced sulfur content and a liquid hydrogen fluoride solution of said sulfur-containing reaction product from the mixture produced in the contacting operation.
- 30 2. A process which comprises sweetening a cracked sour hydrocarbon oil, adjusting the olefin:disulfide molar ratio of said oil to about one and contacting said oil with liquid hydrogen fluoride in quantity sufficient at least to form a distinct liquid phase, thereby effecting chemical reaction between said disulfide and said olefin to form a hydrogen fluoride-soluble sulfur-containing reaction product, and thereafter separating a hydrocarbon oil of reduced sulfur and olefin content and a liquid hydrogen fluoride solution of said sulfur-containing reaction product from the mixture produced in the contacting operation.
- 35 3. In a multi-stage process of removing a hydrocarbon disulfide contained in a hydrocarbon oil, the steps of contacting said hydrocarbon oil in a plurality of stages with concentrated hydrogen fluoride in quantity sufficient at least to form a distinct liquid phase with an added olefinic hydrocarbon in an amount such that the olefinic hydrocarbon:disulfide molar ratio is less than one in any stage but the total olefinic hydrocarbon:disulfide molar ratio in all the stages
- 40 4. In a multi-stage process of removing a hydrocarbon disulfide contained in a hydrocarbon oil, the steps of contacting said hydrocarbon oil in a plurality of stages with concentrated hydrogen fluoride in quantity sufficient at least to form a distinct liquid phase with an added olefinic hydrocarbon in an amount such that the olefinic hydrocarbon:disulfide molar ratio is less than one in any stage but the total olefinic hydrocarbon:disulfide molar ratio in all the stages
- 45 5. In a multi-stage process of removing a hydrocarbon disulfide contained in a hydrocarbon oil, the steps of contacting said hydrocarbon oil in a plurality of stages with concentrated hydrogen fluoride in quantity sufficient at least to form a distinct liquid phase with an added olefinic hydrocarbon in an amount such that the olefinic hydrocarbon:disulfide molar ratio is less than one in any stage but the total olefinic hydrocarbon:disulfide molar ratio in all the stages
- 50 6. In a multi-stage process of removing a hydrocarbon disulfide contained in a hydrocarbon oil, the steps of contacting said hydrocarbon oil in a plurality of stages with concentrated hydrogen fluoride in quantity sufficient at least to form a distinct liquid phase with an added olefinic hydrocarbon in an amount such that the olefinic hydrocarbon:disulfide molar ratio is less than one in any stage but the total olefinic hydrocarbon:disulfide molar ratio in all the stages
- 55 7. In a multi-stage process of removing a hydrocarbon disulfide contained in a hydrocarbon oil, the steps of contacting said hydrocarbon oil in a plurality of stages with concentrated hydrogen fluoride in quantity sufficient at least to form a distinct liquid phase with an added olefinic hydrocarbon in an amount such that the olefinic hydrocarbon:disulfide molar ratio is less than one in any stage but the total olefinic hydrocarbon:disulfide molar ratio in all the stages
- 60 8. In a multi-stage process of removing a hydrocarbon disulfide contained in a hydrocarbon oil, the steps of contacting said hydrocarbon oil in a plurality of stages with concentrated hydrogen fluoride in quantity sufficient at least to form a distinct liquid phase with an added olefinic hydrocarbon in an amount such that the olefinic hydrocarbon:disulfide molar ratio is less than one in any stage but the total olefinic hydrocarbon:disulfide molar ratio in all the stages
- 65 9. In a multi-stage process of removing a hydrocarbon disulfide contained in a hydrocarbon oil, the steps of contacting said hydrocarbon oil in a plurality of stages with concentrated hydrogen fluoride in quantity sufficient at least to form a distinct liquid phase with an added olefinic hydrocarbon in an amount such that the olefinic hydrocarbon:disulfide molar ratio is less than one in any stage but the total olefinic hydrocarbon:disulfide molar ratio in all the stages
- 70 10. In a multi-stage process of removing a hydrocarbon disulfide contained in a hydrocarbon oil, the steps of contacting said hydrocarbon oil in a plurality of stages with concentrated hydrogen fluoride in quantity sufficient at least to form a distinct liquid phase with an added olefinic hydrocarbon in an amount such that the olefinic hydrocarbon:disulfide molar ratio is less than one in any stage but the total olefinic hydrocarbon:disulfide molar ratio in all the stages
- 75 11. In a multi-stage process of removing a hydrocarbon disulfide contained in a hydrocarbon oil, the steps of contacting said hydrocarbon oil in a plurality of stages with concentrated hydrogen fluoride in quantity sufficient at least to form a distinct liquid phase with an added olefinic hydrocarbon in an amount such that the olefinic hydrocarbon:disulfide molar ratio is less than one in any stage but the total olefinic hydrocarbon:disulfide molar ratio in all the stages

11

a liquid hydrogen fluoride solution of said sulfur-containing reaction product, respectively.

4. The process of claim 3 wherein the temperature in each stage is maintained between about 0° F. and about 200° F.

5. The process of claim 1 wherein said mercaptan-containing hydrocarbon oil is gasoline.

6. The process of claim 1 wherein said mercaptan-containing hydrocarbon oil is kerosene.

7. The process of claim 2 wherein said cracked 10 sour hydrocarbon oil is gasoline.

8. The process of claim 2 wherein said cracked sour hydrocarbon oil is kerosene.

9. The process of claim 3 wherein said hydrocarbon oil is gasoline.

10. The process of claim 3 wherein said hydrocarbon oil is kerosene.
